The ornamental design for a trolling motor foot pad base, as shown and described.

DESCRIPTION**U.S. PATENT DOCUMENTS**

1,671,169 A	5/1928	Swain
2,804,838 A	9/1957	Moser
2,902,967 A	9/1959	Wanzer
3,023,633 A	3/1962	Tudos, Jr.
3,246,915 A	4/1966	Alexander
3,470,844 A	10/1969	Johns et al.
3,598,947 A	8/1971	Osborn
3,707,939 A	1/1973	Berg

FIG. 1 is a perspective view of a trolling motor foot pad base of the present invention;

FIG. 2 is a top plan view thereof;

FIG. 3 is a left end elevational view thereof;

FIG. 4 is a right end elevational view thereof;

FIG. 5 is a front elevational view thereof;

FIG. 6 is a rear elevational view thereof; and,

FIG. 7 is a bottom plan view thereof.

The broken lines in the drawings are for illustrative purposes only and form no part of the claimed design.
